UNITED STATES PATENT OFFICE.

PAUL RISSMAN, OF DETROIT, MICHIGAN.

FASTENER MAKING AND DRIVING TOOL.

Application filed January 16, 1922. Serial No. 529,730.

To all whom it may concern:

Be it known that I, PAUL RISSMAN, a citizen of the United States, and residing at Detroit, in the county of Wayne and State of Michigan, have invented a new and Improved Fastener Making and Driving Tool, of which the following is a specification.

This invention relates to portable tools for forming fastening devices, such as staples, from wire, and for driving the fasteners as they are produced, and its object is to provide a tool of this character which may be operated by compressed air or other fluid, which shall be of such small size that it can be readily handled, and which will produce and deliver only one fastener at each actuation of the control mechanism.

10 This invention consists in a supporting handle, an air cylinder carried thereby and a piston in the cylinder, a shaft rotated by the piston, a fastener forming device actuated by the shaft and a fastener driving device actuated by the piston.

15 It further consists in a manually actuated valve for controlling the flow of air to said cylinder and automatic means for causing the valve to close after each rotation of said shaft.

20 It also consists in the novel details of construction illustrated in the accompanying drawings and particularly pointed out in the claims.

25 In the accompanying drawings, Fig. 1 is a plan of this fastener forming and driving tool. Fig. 2 is a side elevation thereof. Fig. 3 is a central section parallel to the view in Fig. 2. Figs. 4 and 5 are sections on the lines 4—4 and 5—5 of Fig. 3. Fig. 6 is a perspective of the forming anvil. Fig. 6^a is an end view of the same. Fig. 7 is a front and Fig. 8 is a rear elevation of this tool. Figs. 9 to 14 inclusive are sections on the lines 9—9 to 14—14 inclusive respectively of Fig. 3. Fig. 15 is a perspective of the driving ram. Fig. 16 is a perspective of a staple former. Fig. 17 is a perspective of a guide therefor. Fig. 18 is a view of a staple. Figs. 19 to 26 inclusive are diagrams illustrating the positions of the fastener forming and driving devices. Fig. 27 is a plan and Fig. 28 is an elevation of the mutilated gear which

drives the feeding device for the wire from which the fasteners are formed.

Similar reference characters refer to like parts throughout the several views.

The type of fastener which is formed by the particular tool shown in the drawings is a staple A illustrated in Fig. 18 and consists of a central bar 1 and two legs 2. The tool embodies a case consisting generally of a handle 3—3^a which may be provided with ribs 4 to assist the operator in holding the tool, and in a head 5—5^a on which is mounted a reel for the supply of wire from which the fasteners are formed. The handle and head together consists of two parts 3—5 and 3^a—5^a, held together by the screws 6.

In the lower part of the handle (Fig. 3) and integral with the part 3 of the case is a valve chamber 7 into which connects the nipple 8 adapted to receive the coupling 9 of the air-hose 10. A washer 12 may be mounted in the valve chamber and constitutes a seat for the valve 13 which is normally held on its seat by a spring 14. The stem 15 is reduced intermediate its ends to permit air to flow to the conduit 16 (Fig. 12) which connects to this valve chamber and to the air cylinder.

The head portion 5 of the case includes a cylinder 17 in which a piston 18 is slidable and a rod 19 is connected to the piston. The cylinder head 20 has a small passage 21 which connects one end of the valve chamber 22 to the passage 23 leading to the interior of the tool. The opposite or inner end of the valve chamber opens directly into the interior of the tool. In this valve chamber 22 is a valve 24 having a reduced intermediate portion 25 and which opens and closes the ports 26 and 27 connecting to the cylinder. Adjacent the valve chamber 22 and connecting to the intermediate part thereof by means of a passage 28 is a small and short chamber 29 (Fig. 10) into which connects the conduit 16 as indicated in dotted lines in Fig. 8. At each depression of the valve 13, therefore, compressed air is admitted to the valve chamber. This cylinder and the parts connected thereto is therefore a pneumatic motor.

A bracket 31 projects inwardly from the side 3 and constitutes a bearing for the

main shaft 32, which makes one rotation for each fastener, a nut 33 holding the shaft in position. On this shaft are secured a crank disk 34 which is actuated by the 5 piston rod 19, an eccentric 35 which actuates the staple forming ram, an eccentric 36 which actuates the valve 24, and a mutilated gear 37 which actuates the feeding mechanism for the wire. A connecting rod 10 38 extends from the eccentric 35 to the valve 25 being connected thereto by a pin 38^a. When the valve is at the left or inner end of its stroke, air passes from the conduit 16 and chamber 29 into the valve chamber 22 15 between the enlarged ends of the valve 25 and through the port 26 into the cylinder 17, while air from the opposite end of the cylinder passes through the port 27 into the outer end of the valve chamber, through the 20 passage 21 into the passage 23 and into the interior of the handle. When the valve is at the other end of the valve chamber, air from the inner end of the cylinder passes through the port 26 directly into the handle, 25 while air from the chamber 29 passes through the port 27 into the outer end of the cylinder. Each enlarged end of the valve uncovers the adjacent port at each 30 end of its stroke.

Attached to the top of the part 5 of the case is a stamping consisting of a base 39 and a rim 40 which has a slot 41 through which the staple wire 42 may run. A hub 43 attached to the base 39 constitutes the 35 bearing for a sleeve 44 of a spool which has two sides 45 and 46, a drum 47 and spring fingers 48 having nibs 49 adapted to engage in the groove 50 in the hub 43 to retain the spool in position. The spool runs freely on 40 the hub.

Formed on the outside of the part 3—5 of the case is an elongated boss 52, shown in elevation in Fig. 2 and in section in Fig. 29. In this boss is a long bearing sleeve 53 and short bearing sleeve 54 which carry a shaft 55 having a grooved feed roller 56 at one end and a gear 57 at the other provided with proper teeth to mesh with the mutilated gear 37. The number of teeth on this 45 mutilated gear is sufficient to feed the wire 42 for one staple.

Adjacent the boss 52 is a shorter boss 58, in which is a bearing sleeve 59 for the shaft 50. On this shaft is a grooved roller 61 55 which presses the wire 42 against the roller 56. A case 62 is attached to the plate 121 which is secured in position by the screws 126. This case normally encloses the feed rollers. In order to stop these rollers so 60 that the mutilated gear 37 will always properly mesh with the gear 57 on the shaft 55, the roller 56 is provided with two notches 126, directly opposite each other into which the end of the spring 63 engages whenever 65 the roller has made a half rotation.

Attached to the extensions 64 and 64^a of the case is a guide plate 65 formed with a hole 66 to admit the staple wire 42, with two lugs 67 to carry the pivot 68 for the forming anvil 69 and two guide ribs 70 for the forming ram 72. The forming ram is slidable in this guide and the corner 73 formed thereon acts as a shear member to cut the wire 42. The incline of this cutting edge 75 serves to point the ends of the legs 2 of the staple, as shown in Fig. 18. The forming ram has a pair of cam lugs 74 to lift the forming anvil out of the path of the driving ram and a cylindrical boss 75 on its lower side (Fig. 3) to receive one end of a connecting rod 76 which is mounted on the eccentric 35. At each rotation of the shaft 32 the forming ram makes one complete forward and back stroke.

The staple is formed on the forming anvil 85 69 which has two ears 77 which extend sufficiently to rest on the ribs 70 of the guide 80 65, and has a central boss 78 which is adapted to extend down between the ribs 79 on the forming ram. When the forming ram is at its inner position, the rollers 56 and 90 61 feed a proper length of wire across the space between the ribs 70. Thereupon the forming ram moves forward and first 95 shears the wire, then moves the severed piece A up to the boss 78 on the forming anvil, then bends the ends of this piece A against the sides of this boss to produce a staple, and finally lifts the boss 78 above the level of the guide ribs 79 by means of the inclined lugs or cams 74. The anvil is normally held down by the spring 120 carried by a cap 121.

Slidable between the ribs 79 is the driving ram 81, shown in Fig. 15, which has a cylindrical boss 82 adapted to extend in a hole in one end of the piston rod 19. Mounted in the piston rod just back of the boss 82 is a pin 83 which receives one end of the connecting rod 84 which is also mounted on 105 a crank pin 85 on the disk 34.

Attention is now directed to Figs. 19 to 26 inclusive. The piston rod is omitted and the connecting rod 84 is shown connected to the boss 82 for the sake of clearness. The connecting rod 76 is shown dotted as is also the eccentric 35. The parts are shown at the normal stationary positions in Fig. 19, which shows the eccentric 35 has a lead of about ten degrees over the crank pin 85. When air is admitted to the inner end of the cylinder, the shaft 32 is rotated in the direction of the arrows in Figs. 21 and 22. At the positions shown in Fig. 20, the wire 42 is fed inward, this being completed at Fig. 21. When the parts are as shown in Figs. 23 and 23^a, the wire has been severed and carried forward until it is pressed against the boss 78 of the forming anvil. About forty degrees of rotation 110 120 125 130

of the shaft completes the forming of the staple and twenty five degrees more causes the cam lugs 74 to lift the boss 78 on the anvil 69 out of the path of the staple and 5 of the driving ram 81. This driving ram engages the staple about fifty-five degrees before the outer end of its stroke, as shown in Fig. 25, and during these fifty-five degrees the staple is pushed out of the guide 10 on the forming ram for the driving ram. The driving and forming rams then return to the initial positions shown in Fig. 19. Attention is called to Fig. 4, which 15 shows the driving ram, the piston rod and piston in the most withdrawn positions and the eccentric 35, connecting rod 76 and forming ram only about ten degrees advanced from such position. The crank disk has two inclined cam faces 20 84 and 85, a notch 86 spaced from the notch by a circular portion 87, and a substantially spiral portion 88 between the circular portion 89 and the cam 85. A pin 90 carried by the part 5^a supports an arm 92 which carries a roller 93 pressed against the 25 crank by the spring 94.

When the parts are as shown in Fig. 4, the 30 crank 34 is on center, the pin 85 being in the line of movement of the pin 83. Any pressure on the piston 18 would be ineffectual to turn the shaft 32. But the pressure of the roller 93 on the inclined surface 85 will turn the crank off the center so that air admitted between the head 20 and the piston may turn the shaft. In a similar manner, 35 the roller 93 and inclined face 84 serve to prevent the crank from stopping on the other center.

Just before the notch 86 reaches the roller 40 93, the air entering at the valve 13 is cut off, as will be explained, so that the pneumatic motor has not sufficient force to force the roller 93 out of this notch after it has dropped into the notch, so that the parts 45 stop in about the position shown in Fig. 19.

Referring now to Figs. 3, 11 and 27, a pin 50 95 is mounted in the part 3 and serves as a pivot for the trigger 96 and the plate 97. The trigger has a finger-piece 98 extending outside the case and a spring 99 to hold the upper end of the trigger outward. On a small arm 100 of the trigger and on the pin 102 carried thereby is a lever 103 whose lower arm has a pin 104 at its end adapted 55 to project into the slot 105 in the plate 97, and a shoulder 106 adapted to contact with the top of this plate 97 toward the pivot 95 from this slot. The upper end of the upper arm of the lever is adapted to be engaged by a cam plate 107 carried by a pin 108 mounted in a hole 109 in the mutilated gear 37.

A spring 110 connects an arm 111 on the 60 lever 103 to the plate 97 and an adjustable screw 112 mounted in a lug 113 on the part

3 limits the upward movement of the plate 97. When the trigger is pressed in, the lever 103 presses down the plate 97 and the valve 13, admitting air to the conduit 16 and to the valve chamber 22, causing the motor to 70 actuate the shaft 32. The trigger is held in to hold down the valve. But when the shaft 32 has made one rotation, the cam plate 107 strikes the upper end of the lever 103, pressing it outward and moving inward the lower 75 end thereof, causing the shoulder 106 to move in from over the pivot wall of the slot 105 in the plate 97 to permit the spring 110 to lift this plate. The spring 14 now closes the valve 13 and the motor stops. 80

When the trigger is released, the spring 99 swings out the pivot 102 for the lever 103, this spring being stronger than the spring 110, and as this lifts the shoulder 106 above the plate 97, the spring 110 swings the lower 85 end of this lever 103 outward and carries the shoulder 106 to the position shown in Fig. 3. The trigger may now be pressed inward to again open the valve 13.

The details and proportions of the various parts of this tool may all be changed by those skilled in the art without departing from the spirit of my invention as set forth in the following claims. 90

I claim:—

1. In a staple forming and driving tool, a case, a staple forming mechanism and a staple driving device, said staple forming mechanism comprising a normally stationary member adapted to extend into the path of the staple driving device and a movable member adapted to bend wire around the normally stationary member to form a staple and then lift the stationary member out of the path of the driving device, and means 100 to actuate said members consecutively, comprising a pneumatic motor and manually operated means to control the operation of the motor. 105

2. In a staple forming and driving tool, a case, a staple forming mechanism and a slide- 110 able staple driving device, the staple forming mechanism comprising a pivoted member adapted to swing into the path of the staple driving device and around which the

staple is bent and a slideable member adapted to shear the staple wire and bend it around the pivoted member and then lift the pivoted member out of the path of the driving device, and means to force said slideable member and the driving device outwardly consecutively comprising a driving shaft, connections between the driving shaft and said slideable member and the driving device, a pneumatic motor to actuate the driving shaft, and manually operated means to control the motor. 115 120

3. In a staple forming and driving tool, a case, a staple forming mechanism and a slide- 125 able staple driving device, the staple form-

- ing mechanism comprising a pivoted member adapted to swing into the path of the staple driving device and around which the staple is bent and a slidable member adapted to shear the staple wire and bend it around the pivoted member and then lift the pivoted member out of the path of the driving device, and means to force said slidable member and the driving device outwardly 50 consecutively comprising a shaft and a pair of eccentrics thereon and connecting rods extending from the eccentrics to said slidable parts.
4. In a staple forming and driving tool, 15 a case and a guide therein, a shearing and forming member slidable in the guide, means for feeding wire thereto, said shearing and forming member having longitudinal guides, a staple driving ram slidable in said guides 20 on the shearing and forming member, a cylinder, a piston slidable therein, a piston rod connecting the piston to said driving ram, a shaft, a crank thereon, a connecting rod pivoted to the piston rod and to said crank to 25 turn the shaft, and means connecting the shearing and forming member to said shaft.
5. In a staple forming and driving tool, a case and a guide therein, a shearing and forming member slidable in the guide, 30 means for feeding wire thereto, said shearing and forming member having longitudinal guides, a staple driving ram slidable in said guides on the shearing and forming member, a cylinder, a piston slidable therein, a piston rod connecting the piston to 35 said driving ram, a shaft, a crank thereon, a connecting rod pivoted to the piston rod and to said crank to turn the shaft, means connecting the shearing and forming member to 40 said shaft, and means operated by said shaft to actuate the means for feeding the wire.
6. In a staple forming and driving tool, a case and a guide therein, a shearing and forming member slidable in the guide, 45 means for feeding wire thereto, said shearing and forming member having longitudinal guides, a staple driving ram slidable in said guides on the shearing and forming member, a cylinder, a piston slidable therein, a piston rod connecting the piston to 50 said driving ram, a shaft, a crank thereon, a connecting rod pivoted to the piston rod and to said crank to turn the shaft, means connecting the shearing and forming member to 55 said shaft, a valve operatively connected to said shaft for controlling the operation of said piston, and a manually operable valve to admit air under pressure to said first 60 named valve.
7. In a staple forming and driving tool, a case and a guide therein, a shearing and forming member slidable in the guide, means for feeding wire thereto, said shearing and 65 forming member having longitudinal guides,
- a staple driving ram slidable in said guides on the shearing and forming member, a cylinder, a piston slidable therein, a piston rod connecting the piston to said driving ram, a shaft, a crank thereon, a connecting rod pivoted to the piston rod and to said crank to turn the shaft, means connecting the shearing and forming member to said shaft, and a manually operable valve to admit air under pressure to said cylinder. 70
8. In a staple forming and driving tool, a case and a guide therein, a shearing and forming member slidable in the guide, means for feeding wire thereto, said shearing and forming member having longitudinal guides, a staple driving ram slidable in said guides on the shearing and forming member, a cylinder, a piston slidable therein, a piston rod connecting the piston to said driving ram, a shaft, a crank thereon, a connecting rod pivoted to the piston rod and to said crank to turn the shaft, means connecting the shearing and forming member to said shaft, a valve to admit fluids under pressure to said cylinder, a trigger to open the valve, and means connected to said shaft to release the valve from said trigger. 80
9. In a staple forming and driving tool, a case, a staple forming device and a staple driving device therein, a pneumatic motor, means operatively connecting the motor to the forming and driving devices, a valve to control the admission of air to said motor, a manually operable trigger to open said valve, a spring to close the valve, and means operated by said motor to disconnect the trigger from the valve after the driving of a staple to permit the spring to close the valve. 85
10. In a staple forming and driving tool, a case and a guide therein, a shearing and forming member slidable in the guide, means for feeding wire thereto, said shearing and forming member having longitudinal guides, a staple driving ram slidable in said guides on the shearing and forming member, a cylinder, a piston slidable therein, a piston rod connecting the piston to said driving ram, a shaft, a crank thereon, a connecting rod pivoted to the piston rod and to said crank to turn the shaft, and means connecting the shearing and forming member to said shaft, said crank being in the form of a disk having cam faces formed on its periphery, and a spring pressed roller engaging said periphery to prevent the crank from stopping on center. 90
11. In a staple forming and driving tool, the combination of a case, a main shaft therein, a wire-holding spool rotatable on the case, a feed shaft on the side of the case at an angle to the main shaft, gearing whereby the feed shaft is driven intermittently by the main shaft, an idler shaft mounted parallel to the feed shaft, feed rolls for the wire 100

- mounted on the feed and idler shafts, staple shearing and forming means in the case, means operatively connecting the same to the main shaft, a staple driving ram mounted in said case, a pneumatic motor, and means to operatively connect the motor to the main shaft and to the driving ram. 5
12. In a tool for forming and driving fasteners, the combination of a guide, a 10 shearing and forming member slidable thereon, a forming anvil pivotally mounted on the guide to cooperate with the slidable member to form staples, means to supply wire to said tool to form the fasteners, a driving ram 15 for the fasteners, a pneumatic cylinder and a piston therein, a piston rod connecting to said driving ram, and means operatively connecting to said piston rod to said slidable member. 20
13. In a staple forming and driving tool, the combination of a case and a guide therein, a shear member slidable in the guide, a driving ram slidable on the shear member, a shaft to actuate the shear member, a pneumatic cylinder and piston to actuate the ram 25 and shaft, and an anvil pivoted on said guide on which the staples are bent, said anvil having a boss normally extending into the path of the driving ram, and cam lugs on the shear member adapted to move the boss on 30 the anvil out of the path of the driving ram. 14. In a staple forming and driving tool, the combination of a case, a main shaft therein provided with a crank and two eccentrics, a guide in the case, a shear member slidable 35 on the guide, a connecting rod between the shear member and one eccentric, a cylinder attached to the case, a piston and piston rod slidable in the cylinder, a connecting rod between the piston rod and crank, a driving 40 ram for the staples and means connecting the ram to the piston rod, a valve to control the piston, and a connecting rod between the second eccentric and said valve.

PAUL RISSMAN.
